W. J. KELLY, ALL OF CLINTON, IOWA.

DRIVING MECHANISM FOR WASHING-MACHINES.

1,075,175.

Specification of Letters Patent.

Patented Oct. 7, 1913.

Application filed April 1, 1912. Serial No. 687,894.

To all whom it may concern:

Be it known that I, ORLA H. WATKINS, citizen of the United States of America, and resident of Clinton, Clinton county, Iowa, 5 have invented a new and useful Driving Mechanism for Washing-Machines, of which the following is a specification.

The object of this invention is to provide improved means for driving a device such as 10 the dolly shaft or agitator of a washing machine.

A further object of this invention is to provide improved means for selectively operating or driving different devices such as 15 the agitator of a washing machine and the rolls of a clothes-wringer.

A further object of this invention is to provide improved means for throwing the driving mechanism out of gear in respect of 20 either or any device driven thereby.

My invention consists in the construction, arrangement and combination of elements hereinafter set forth, pointed out in my claims and illustrated by the accompanying 25 drawing, in which—

Figure 1 is a side elevation illustrating a washing machine to which my improved mechanisms are applied. Fig. 2 is a side elevation at right angles to Fig. 1. Fig. 3 30 is a plan of the apparatus shown in Figs. 1 and 2. Fig. 4 is a plan, partly in section, on an enlarged scale, illustrating parts of the driving mechanism. Fig. 5 is an elevation, partly in section, on an enlarged scale, 35 illustrating means for applying power to a device to be driven such as an agitator shaft. Fig. 6 is a bottom plan of the apparatus. Fig. 7 is a detail elevation, partly in section, 40 illustrating means employed for supporting a foot lever in different positions. Fig. 8 is an elevation, partly in section, of a gear case and gear therein.

In the construction of the apparatus as shown the numeral 10 designates a support, 45 in this instance a conventional tub for a washing machine, which support is carried by legs 11. A prime mover 12, in this instance a conventional electric motor, is mounted on the bottom of the support 10 and a shaft 13 thereof extends beyond one 50 side of the support and carries a pulley 14. A gear case 15 of any desired form and con-

struction is mounted on a portion of the support, in this instance the horizontal member 16 of a wringer-stand fixed to the tub 55 member. The gear case 15 is provided with horizontal bearings 17 and a worm shaft 18 is journaled horizontally in said bearings and extends therefrom at both ends. The worm shaft 18 is provided with a worm 19 60 within the gear case 15 and is provided with a pulley 20 outside said gear case, which pulley is adapted to be connected by a belt 21 to the pulley 14 of the motor. The primary function of the motor 12 is to drive the worm 65 shaft 18 and worm 19 thereon in one direction.

A clothes-wringer 22 of any desired and suitable construction is fixed to an upright member 23 of the wringer-stand and the 70 lowermost wringing roll 24 thereof carries on one end a pinion 25. A countershaft 26 is journaled in suitable bearings in the wringer frame and in the gear case 15 and extends entirely through said frame and gear 75 case parallel with and below the rolls of the wringer and at right angles to and above the worm shaft 18. The countershaft 26 also is arranged to be moved longitudinally in its bearings.

A worm gear 27 is mounted loosely on the countershaft 26 within the gear case 15 and a bevel pinion 28 is formed integral with or fixed to said worm gear and also loosely surrounds the countershaft. The counter- 85 shaft 26 is formed with one or more studs 29 extending laterally therefrom and adapted at times to engage with corresponding studs on the hub of the bevel pinion 28. A bevel pinion 30 is arranged opposite to the 90 pinion 28 and is journaled in the gear case 15. The bevel pinion 30 also loosely embraces the countershaft 26 and provides a bearing therefor. The countershaft 26 is formed with one or more studs 31 extending 95 laterally therefrom and adapted for engagement at times with corresponding lugs 32 on the inner end of the hub of the bevel pinion 30.

A crank-shaft 33 is journaled in a bearing 34 and in a bearing 35 of the gear case 15 parallel with the worm shaft 18 and also is arranged for longitudinal movement in 100 said bearings. One end portion of the

crank-shaft 33 extends within the gear case and loosely through a bevel pinion 36 within said case, which pinion meshes with the bevel pinions 28 and 30 at diametrically opposite points. The inner end portion of the crank-shaft 33 carries a transverse pin 37 adapted to be received at times in notches 38 in the hub of the pinion 36 to connect said shaft and pinion for conjunctive rotation. The bearing 34 is fixed to and rises from a stationary member 39, in this instance a portion of the cover of the tub. A movable member 40, such as in this instance a cover for the tub, is connected by arched hinges 41 to the stationary member 39. The movable member 40 is provided with a latch 42 opposite to the hinges 41 whereby it may be detachably secured to the support or tub 10 in closed position. A set collar 43 is mounted on the crank-shaft 33 between the bearings 34 and 35 and is spaced from both bearings. A cam lever 44 is pivoted at one end on the crank-shaft 33 between the set collar 43 and bearing 34 and is formed 25 with one or more cam lugs 45 fitted to notches in the adjacent end of the bearing 34. A link 46 is pivoted at one end to the inner end of the cam lever 44 and extends obliquely downwardly therefrom and is pivoted at its 30 lower end to an angle plate 47 on the movable member 40 of the tub top. The cam lever 44 is formed with a stop or lug 48 between its ends. A crank 49 is secured by a set screw 50 on the outer end of the crank-shaft 33 and an expansive coil spring 51 is mounted on said crank-shaft and impinges 35 at its respective ends on the bearing 34 and the hub of the crank 49. It is the function of the coil spring 51 to move and hold the 40 crank-shaft 33 outwardly longitudinally in its bearings to the end of inserting the pin 37 in the notches 38 and connecting the pinion 36 and crank-shaft for conjunctive rotation. It is the function of the cam lever 45 44, acting through the cam lugs 45 and adjacent end of the bearing 34, to move the crank-shaft 33 longitudinally in its bearings against the expansive force of the spring 51. It is the function of the stop 45 or lug 48 to engage the link 46 and support the movable member 40 in open position out of contact with the gear case or bearings adjacent thereto.

A device to be driven, such as a dolly shaft or agitator shaft 52, is mounted loosely in a hole in a plate 53 fixed to the movable member 40. The shaft 52 also extends loosely through the movable member 40 and is adapted for rotation and also for rectilinear reciprocation therein and through the plate 53. A crank-arm 54 is formed with an angular aperture in one end receiving and fitting loosely to the shaft 52 and said crank-arm lies on and is movable through 60 an arc in a plane parallel with the plate 53.

A lever 55 is fulcrumed at one end on a stud 56 rising from the plate 53. The lever 55 is of skeleton form, having a large aperture or opening 57 through which the shaft 52 may pass and said opening is of such shape 70 as to permit the lever to be moved through an arc approximating a half circle across the shaft 52. A pin 58 rises from the outer end portion of the crank-arm 54 into a groove 59 formed in and longitudinally of 75 the outer end of the lever 55. By means of the pin 58 and groove 59 motion is transmitted from the lever 55 to the crank-arm 54 to the end of rotating the shaft 52. A block 60 is pivoted at one end on a 80 stud 61 rising from the free end of the lever 55 and a pitman 62 is pivoted at one end to said block and is pivoted at the opposite end to one end of a block 63, the latter block being in turn pivoted to the crank 49. The lines of articulation between the block 60 and stud 61 on one hand and between said block and the pitman 62 on the other hand are at right angles to each other. The lines of articulation between the block 63 and pitman 62 on the one hand and between said block and the crank 49 on the other hand are at right angles to each other. Thus a large degree of flexibility is established between the lever and shaft devices on the movable 95 member 40 and the shaft and crank devices carried by the bearing 34, which permits the free and uninterrupted movement of the movable member and devices carried thereby through an arc by articulating on the 100 hinges 41.

It will be observed that when the movable member 40 is moved into open position the shaft 33 is disconnected from the pinion 36 and becomes stationary, thus stopping any 105 movement of the lever and shaft devices on said movable member.

The countershaft 26 carries rigidly a pinion 64, which pinion meshes with the pinion 25 and preferably has longer teeth than the latter pinion in order that it may remain in mesh therewith throughout the range of movement of the countershaft longitudinally.

A bracket 65 is mounted on the member 115 16 at the opposite end of the wringer 22 from the gear case 15 and a bell-crank 66 is fulcrumed on said bracket and has one of its arms extending outward horizontally and the other upright therefrom. The extremity of the upper arm of the bell-crank 66 is bifurcated and it embraces a grooved set collar 67 on the adjacent end portion of the countershaft 26. The lower arm of the bell-crank 66 is pivoted at its outer end to the 120 upper end of a rod 68 and the lower end of said rod is pivoted to a treadle 69 or pedally-operated lever. The treadle 69 is pivoted at one end to a plate 70 carried by the legs 11 of the support and is upheld 125 130

normally by a retractile coil spring 71 connecting said lever to the bottom of the support. The outer end portion of the treadle 69 extends through a slot 72 in a plate 73 mounted in upright position on one of the legs 11. The plate 73 is formed with a shoulder 74 in the slot 72 and the treadle 5 may be arranged in engagement with the shoulder to hold the countershaft 26 in neutral position as shown in Fig. 4, the lugs 29, 10 31 and 32 being wholly disengaged. In the neutral position as shown the shaft 26 is stationary and does not operate the wringer rolls in either direction. Or, the treadle 15 may be adjusted into the upper part of the slot 72 and, acting through the connections therewith, will move the countershaft 26 so as to bring the studs 29 into engagement with the hub of the bevel pinion 28 and 20 cause said shaft to be rotated in one direction and in turn rotate the wringer rolls. Or, the treadle 69 may be depressed pedally to the bottom of the slot 72 and in such position act through the connections therewith 25 and move the countershaft 26 in the opposite direction so as to disengage the studs 29 from the bevel pinion 28 and engage the studs 31 with the studs 32 on the bevel pinion 30 to the end of driving the countershaft 30 in the opposite direction rotatively through the medium of the latter bevel pinion and in turn driving the wringer rolls in the opposite direction.

I claim as my invention—

35 1. A driving mechanism, comprising a suitable support, a device to be driven journaled in said support, a motor on said support, a gear case on said support, a worm gear in said case, driving connections between the motor and worm gear, a shaft 40 mounted for rotation and rectilinear reciprocation on said support, detachable connections between said shaft and worm gear, crank connections between said shaft 45 and the device to be driven, a spring acting to move said shaft in one direction, and cam lever devices acting to move said shaft against the resistance of the spring.

2. In a driving mechanism, a support 50 having a stationary and a movable member, arched hinges connecting said members, bearings on the stationary member, a shaft loosely mounted in said bearings, a crank on said shaft, a spring between said bearing 55 and crank, a set collar on said shaft, and cam lever devices connected to the movable member and acting between said set collar and bearing whereby the shaft may be moved rectilinearly against the force of 60 said spring.

3. In a driving mechanism, a support comprising a stationary element and a second element hingedly connected to the stationary element, a device to be driven as-

sociated with said second element, a shaft to drive said device and supported from said first element, gearing for driving said shaft, and connections operated by the second element when the latter is moved on 65 its hinges for disconnecting said gearing and said shaft.

4. In a driving mechanism, a support comprising a stationary element and a second element hingedly connected to the stationary element, a device to be driven associated with said second element, an axially movable shaft to drive said device and supported from said first element, gearing for driving said shaft, the axial movement 70 of the latter providing for its connection with or its disconnection from said gearing, and connections controlled by the second element when the latter is moved on 75 its hinges for producing an axial movement of 80 said shaft.

5. In a driving mechanism, a support comprising a stationary element and a second element hingedly connected to the stationary element, a device to be driven associated with said second element, an axially movable shaft to drive said device and supported from said first element, gearing for driving said shaft, the axial movement of 85 the latter providing for its connection with or its disconnection from said gearing, and connections controlled by the second element when the latter is moved on 90 its hinges for producing an axial movement of 95 said shaft, the connections comprising a spring which gives the shaft a thrust in one direction and a cam lever connected to the second element and which gives the shaft a thrust in the opposite direction and against the resistance of said spring.

6. In a driving mechanism, opposed bevel pinions and an intermediate bevel pinion meshing with said opposed pinions, a shaft upon which the opposed bevel pinions are loose and which may be driven by either of 105 said opposed pinions, a second shaft upon which the intermediate pinion is loose and which may be connected to or disconnected from said intermediate pinion, a movable member and a driven device carried thereby 110 and operated by said second shaft and connections controlled by said movable member for disconnecting the second shaft from the intermediate pinion without affecting the engagement of the latter with the opposed 115 pinions.

7. In a driving mechanism, a movable supporting member, a driven device driven thereby, a stationary supporting member to which the movable member is hinged, a 120 shaft carried by the stationary member, flexible driving connections between the shaft and the driven device, gearing for driving the shaft, and connections con-

trolled by the movement of the hinged supporting member for disconnecting the shaft from said gearing.

8. In a driving mechanism, a spring held axially movable shaft, gearing for driving the same, a driven device, flexible connections between the shaft and the driven device, a hinged supporting member carrying the driven device and connections operated by the hinged member when the latter is

raised for moving the shaft axially against the resistance of its spring, thereby to disconnect the shaft from said gearing.

Signed by me at Clinton, Iowa, this 29th day of November, 1911.

ORLA H. WATKINS.
